UNITED STATES PATENT OFFICE

JOHN SBROLLA, OF ATLANTIC CITY, NEW JERSEY

SWIMMING GLOVE

Application filed September 3, 1929. Serial No. 390,139.

This invention relates to apparel and more particularly to a glove adapted to be worn when swimming.

When swimming many persons fail to keep their fingers and thumbs pressed close together thereby leaving spaces between the fingers and thumbs through which water may pass. This reduces the speed at which they may travel through the water and in addition makes swimming more difficult. Therefore, one object of the invention is to provide a glove which may be applied to a person's hand and constitute a shield for spaces between the fingers and thumbs. This not only prevents water from passing between the fingers and thumbs but in addition allows the fingers and thumbs to be spread apart thereby increasing the surface which acts against the water when swimming and allows a person to swim easier and faster.

Another object of the invention is to provide a device of this character consisting of a sheet of rubber or rubberized fabric shaped to conform to a person's hand when the fingers and thumb are spread and thereby allow a person to swim with their fingers and thumb spread apart while at the same time allowing the fingers to be disposed against each other if so desired.

Another object of the invention is to provide improved means for retaining the sheet in proper engagement with a person's hand and fingers and allow the device to be easily applied but prevent it from being liable to accidentally work loose.

Another object of the invention is to provide a device of this character in which water cannot collect and cause it to be uncomfortable when worn.

The invention is illustrated in the accompanying drawing wherein,

Figure 1 is a view showing the improved swimming device applied to a person's hand,

Figure 2 is a transverse sectional view taken along the line 2-2 of Figure 1 with the hand omitted,

Figure 3 is a sectional view taken along the line 3-3 of Figure 1, and

Figure 4 is a fragmentary view showing the wrist encircling band laid flat.

This improved swimming device consists of a sheet 1 formed of soft rubber or rubberized fabric of sufficient thickness to prevent it from tearing easily but at the same time sufficiently thin to cause it to be pliable and allow the fingers and thumb of a hand to which it is applied to be spread as shown in Figure 1 or pressed close together. The sheet conforms to the contour of a hand having the thumb and fingers spread and has a wide forward portion along which the thumb and fingers extend as shown in Figure 1. The sheet tapers rearwardly to follow the outline of a person's hand and at its rear end terminates in a neck or reduced extension 2 to fit against the wrist. Wings 3 project from opposite sides of the neck to form a wrist-encircling band and are disposed at a rearward incline so that they will fit properly about the wrist. In order to allow the ends of the wings to be secured one in overlapped relation to the other there has been provided snap fasteners 4 and 5 but it will be understood that buttons and button-holes may be substituted for the snap fasteners or other specific form of fastening means employed.

When this swimming glove or appliance is in use it is to be applied against the palm of a person's hand with its rear end held in place by the side wings or arms 3 engaged about the wrist and the forward portion held against the fingers and thumb. In order to retain the forward portion in engagement with the fingers and thumb there has been provided loops or bands 6 which fit about the thumb and fingers near the upper or inner ends thereof and pockets or stalls 7 into which the ends of the thumb and fingers are thrust. These bands and pockets are either molded integral with the sheet or firmly cemented or otherwise fixed thereto and it is to be understood that when the device is applied for use the thumb and fingers are first thrust through the bands 6 and into the pockets 7 and the wings 3 then secured about the wrist. When so applied the device will be firmly held against a person's hand and a person will be able to freely move the thumb and fingers towards or away from each other. By holding the thumb and fingers close to each

other the hand may be moved easily through the water when reaching forwardly and by spreading the thumb and fingers when moving the hand and arm rearwardly the portions of the sheet between the fingers and thumb and first finger will constitute webs. Therefore, a person will be able to swim with greater ease and rapidity. The fact that the device consists of a sheet secured against the hand, instead of a glove which fits upon the hand and is provided with webs between the thumb and fingers, reduces its weight and makes it more comfortable to wear and also prevents water from accumulating in it. There will be no danger of the device slipping out of proper engagement with a hand but when the side wings 3 are released it can be very easily removed.

Having thus described the invention, I

claim:

A swimming appliance comprising a sheet of dimensions to fit against the hand having the thumb and fingers thereof spread, said sheet being formed of flexible material to permit movement of the thumb and fingers toward and away from each other, the rear portion of the sheet being tapered to fit against a person's wrist and provided with side wings adapted to be secured together about the wrist, bands carried by said sheet and projecting from the rear face thereof to engage about a person's thumb and fingers near their inner ends, and pockets to receive the ends of the thumb and fingers carried by the sheet adjacent its forward edge and projecting from the rear face thereof in transversely spaced relation to each other and having their rear ends open and disposed in facing relation to the bands.

In testimony whereof I affix my signature.
JOHN SBROLLA. [L. S.]
